EYEGLASS DISPLAY RACK OR THE LIKE

William G. Pacelli, Leominster, Mass., assignor to Foster Grant Co., Inc., Leominster, Mass., a corporation of Delaware

Filed May 5, 1961, Ser. No. 65,045

Term of Patent 14 years

(Cl. D80—5)

FIG. 1 is a front elevation of an eyeglass display rack or the like showing my new design.

FIG. 2 is a side elevation thereof.

FIG. 3 is a top plan view thereof.

FIG. 4 is a vertical cross-section thereof taken on line 4-4 of FIGURE 1.

I claim:

The ornamental design for an eyeglass display rack or the like, substantially as shown.
